UNITED STATES PATENT OFFICE.

ANTONIO RAIMONDI, OF MILAN, ITALY.

PACKING.

1,138,413.

Specification of Letters Patent.

Patented May 4, 1915.

Application filed November 10, 1910. Serial No. 591,630.

To all whom it may concern:

Be it known that I, ANTONIO RAIMONDI, merchant, subject of the King of Italy, residing at No. 4 Via San Vicenzino, Milan, in the Kingdom of Italy, have invented certain new and useful Improvements in Packings, of which the following is a specification.

One of the most used forms of packings for rendering the joints of water, gas, air and steam pipes or boxes tight, is the packing of metal gauze and red lead, manganese or other cement.

The sheets of metal gauze, cut in shape of circular rings or in rectangular form, according to the contour of the flanges, whose joints are to be made tight, are liable to get distorted or buckled owing to the unequal stresses they are subject to, while being fitted to the flanges of the pipe joints, steam boxes and the like. This is the reason why the outer edges of the metal gauze packing sometimes project outside the face of the flanges with which they should be flush, or, what is still worse, the inner edges partly obstruct the path of the water, steam or gas, by their projecting inwardly on one side or the other, owing to their having been unequally distended during the making of the joint.

The object of the present invention is to remove the above inconveniences by supplying a substitute for the metal gauze, which is easy to be handled and, not being liable to distortion, secures an exact adjustment of the packing to the faces of the flanges, which are to be made water, steam or gas tight.

According to my invention the circular rings or rectangular frames on which the red-lead, manganese or other cement is laid, do not longer consist of metal gauze, but instead thereof, thin metal plates are resorted to, suiting the form of the flanges and provided with small holes all over their surface.

I usually employ iron sheets of 0.1-0.2 mm. thickness, make the holes circular 1 mm. diameter and 2 mm. distance from center to center, but I do not intend to confine myself to any of the above data, as the thickness of the sheets or plates, the size, shape and number of the holes may vary within very wide limits. Moreover in order to secure the exact fitting of said metal sheets or plates to the flanges of the line of

pipes, which is by no means an easy matter, especially in the case of packings having to be changed along a complete range of pipes already at work, without removing any of the pipes, I provide two handles at the end 80 of the same diameter or line of symmetry of each plate and trace a straight line along said diameter or line of symmetry.

The rings, fitted with such handles, can be most easily mounted in absolutely concentrical position with respect to the flanges, as it is only necessary to that effect to observe the ends of the two handles and cause them to project equal distances on both sides and therefore to be equidistant from the 70 center of the pipe.

In some cases each of the plates may be fitted with more than two handles.

In the accompanying drawing Figure 1 represents a plan view of a packing plate 75 made according to my invention, and Fig. 2, a sectional view on a reduced scale of two pipe-sections joined and provided with the packing plate.

—a— is the annular ring, —b— are the 80 holes and —c— the handles above referred to.

A B is a straight line traced on the plate and passing through the center of the ring.

From Fig. 2 it will be noted that, to form the joint, the annular plate a is interposed 85 between the flanges d of the pipe-sections D, D' and in direct contact with the opposed surfaces of said flanges, the fluid joint being then made by tightening the screw-bolts e in the usual way.

In employing a foraminated thin flat plate for packing, under my invention the very important advantage is obtained over wire gauze packings, which must be embedded in a layer of packing cement or composition, that such cement or composition, which may be red lead or manganese, is not to be used as the packing medium, but need be applied simply at those points of the 90 packing plates where hollows or uneven surfaces occur in the pipe joints. Therefore, while, when, using the wire gauze packing the cement or other composition forms the 95 packing and the wire gauze which is embedded therein acts simply as a carrier therefor, under my invention the thin plate forms substantially the packing proper and requires only an insignificant amount of cement to completely fill the hollows or flaws which may occur in the pipe-joint flanges.

110

Having described my invention and how the same is to be carried out, what I claim is:

1. A joint packing for pipes and inclosures, comprising a flat thin foraminated hard metal plate.
2. A joint packing for pipes and inclosures, comprising a thin flat hard metal plate provided over its surface with minute closely adjacent perforations.
- 10 3. A joint packing for pipes and inclosures, which comprises a flat thin foraminated hard metal plate, provided with handles arranged at opposite points.

4. In a joint packing, the combination of two pipe joints provided with flanges adjacent to one another, in combination with an interposed packing comprising a foraminated thin flat hard sheet metal plate, and means for holding the flanges together. 15

In testimony whereof I affix my signature 20 in presence of two witnesses.

ANTONIO RAIMONDI.
